ISAK ISAACHSEN, OF OSLO, NORWAY, ASSIGNOR TO AKTIESELSKAPET KRYSTAL, OF OSLO, NORWAY.

PROCESS FOR THE CRYSTALLIZATION OF SOLID SUBSTANCES IN A COARSE GRANULAR FORM FROM SOLUTIONS.

Application filed September 10, 1925, Serial No. 55,802, and in Norway September 17, 1924.

It is formerly known that crystallizations from the supersaturated solutions may be caused to grow by circulating them in an apparatus together with the solution. This method is used for instance in vacuum apparatus for the manufacture of common salt. It involves special advantages, if the specific gravity of the suspended granules is not essentially higher or even less than the specific gravity of the liquid or if the liquid is very viscous as is the case for instance in the manufacture of sugar.

But the method has hitherto been afflicted with very great drawbacks, among other things because the creation of new small kernels in the apparatus has taken place completely uncontrolled. If the intensity of production is maintained only moderately high, the liquid will become so highly heaped with crystals that the contents of the apparatus will form a thick mass before the separate granules have obtained moderately large dimensions. If, for instance, the separate granules were cause to grow from 1/100 mm. to 4 mm. in average diameter, their total volume would increase to the 64000000-double one. Therefore, it has been necessary either to remove the precipitations before the granules have attained larger dimensions, such as used in vacuum apparatus for the manufacture of common salt, or it has been necessary to operate the apparatus intermittently, with a low intensity each time new kernels had to be created and as long as they were still small, such as has been proposed in respect of vacuum apparatus for sugar. Otherwise, a superfluous number of new kernels would be formed, because any change requires a comparatively long time owing to the large quantities of liquid in the apparatus, and these small kernels will thereafter grow quite catastrophically, as just intimated.

In addition, one had not by a constrained guiding of the liquid-circulation taken care of maintaining the granules in suspension until they were large enough.

The present invention does away with these inconveniences by combining three elements formerly known separately but never utilized simultaneously hitherto.

1. A constrained guiding of the circulating stream of liquid wherein the kernels are

suspended, with so high velocities that the kernels can nowhere deposit before they have attained the desired size.

2. A regular removal of kernels which have grown to the size desired.

3. A regulation of the number of the small kernels by introducing regularly small kernels or causing them to form automatically in the apparatus or by removing them according as the mass of kernels in the apparatus is increasing or decreasing durably.

The removal of large kernels and the regulated introduction of small kernels in the apparatus need not be quite constant. Small variations play no part.

The important point consists in taking care that the total superficial area of kernels in the apparatus, in spite of the regular removal of the ready-grown ones, is always so large that the said area at a full intensity of the operation can take up the most essential part of the crystallizations.

If the present surface of kernels should be too small and thereby the new formation of small kernels so great that the constant increase of the latter cannot be regulated by the present means for taking out small kernels, the catastrophic growth of these small kernels will transform the contents of the apparatus into a thick mass, before the largest kernels have attained the desired size.

The accompanying drawing illustrates as examples two utilizations of the method diagrammatically. Figure 1 shows an apparatus for continuous manufacture of coarse-granular precipitations by cooling, and Figure 2 an apparatus for continuous manufacture of coarse-granular precipitations by the evaporation of a solution.

In Figure 1, *a* is a vessel having the shape of a closed annular channel and being filled with a solution and a suspension of larger or smaller kernels of the substance to be precipitated. *b* is a propeller which passes the solution in the direction indicated by the arrows. *c* is a cooling device consisting of pipes through which the contents of the apparatus are passing.

The cross sectional areas of the vessel are all over so small that the suspension is taken along and circulates with the liquid.

All superfluous small crystals are removed before having time to grow up, by a pipe *d*.

facing its funnel-shaped opening *e* against the stream so that a portion of the solution will take its way through the pipe *d*, the space *f* and the aperture *g*. As the propeller *b* produces a rotation of the column of liquid, so that the coarser crystals will be forced towards the wall of the vessel by the centrifugal force, the solution passing into the centrally disposed funnel *e* will contain only crystals of smaller dimensions. The quantity of liquid passing through *d* may be regulated by a cock *w*. In comparatively large spaces *f* these small kernels will sink down more or less completely and may be taken out through the cock *h*. The liquid passes on through the aperture *g* into the main stream again.

When the main stream passes by the aperture *g*, a portion of the largest crystals will fall down through *g* and the pipe *i* to the conveyor *k* which removes them from the apparatus. The stream of liquid coming from *e* through *d* prevents smaller crystals which have still not grown to the desired size from falling down through the aperture *g*.

l is a cross which smooths the rotation of liquid produced by the propeller, so that the crystals in the lower part of the apparatus will not be flung against the wall, where they would be less completely taken along by the stream of liquid.

At *m* solution is taken out continuously, at *n*, new solution with a higher temperature and a higher proportion of the dissolved substance is introduced continuously, and at *n*, new, small crystals are introduced, if necessary.

If, by a careful construction of the apparatus, it can be obtained that not too many of new, small crystals are created automatically, the removal of small crystals through *e* and *d* are not necessary. In such case not a higher number of small kernels are introduced through *n*, or not a larger number of new kernels are caused to be created than is necessary to prevent any obstruction of the apparatus. In other words, care is taken systematically that only the same number of small kernels are allowed to grow as the number of large kernels desired to remove. Each small kernel, namely, grows into a large one, and if, therefore, the number of the kernels are not limited while they are small, difficulties must arise.

In Figure 2, *a* is again a vessel of such a shape as to form a closed annular channel. It is filled with a solution carrying a suspension of larger and smaller kernels of the substance or substances to be precipitated. A propeller *b* passes the contents in the

direction indicated by the arrows, *o* is a superheater consisting of pipe through which the liquid and suspension are passing. At the level *p* the liquid is boiling and the steam passes out through *q*.

From a place *r*, where the larger crystals will not arrive owing to an enlargement of the vessel *a*, a pump *s* sucks a solution mixed with small crystals out through a sedimentation compartment *t*, wherein a greater or smaller part of the small crystals are sinking down and may be removed through the cock *h*. At *u* the liquid is then passed into the vessel again. *w* is also a cock by which the quantity of the liquid passing through may be regulated.

From the same place *r* another pump *v* sucks liquid which is free of larger crystals, and drives them up through the removal-aperture *g* for large crystals. The large crystals will fall down through the pipe *i* into the conveyor *k*.

Instead of removing the small crystals by sedimentation in *t*, other known methods may be used, such as for instance a throwing-out in a centrifugal separator, or filtration. Also the known peculiarity may be utilized that small crystals are more easily soluble than large ones, by dissolving the small crystals by passing under-saturated solution into the compartment *t*.

New solution is introduced through the pipe *n*.

If the apparatus does not create itself a sufficient number of new small crystals, no crystals are removed through *r* *t* *h*, but small crystals are introduced from outside through the aperture *n*.

These small crystals introduced from outside, may also be produced in a separate portion of the same apparatus, a higher supersaturation being created here than in other parts, for instance by extra cooling.

I claim:

The method of crystallizing out solid substances from supersaturated solutions thereof wherein the solution and a suspension of granules of the substances circulate cyclically which comprises circulating the solution and suspension as a stream of relatively small cross sectional area whereby the granules are normally positively carried along by the circulating stream, regulating the number of granules before they have materially increased in size, and removing granules from the circulating stream at designated places therein.

In testimony that I claim the foregoing as my invention, I have signed my name.

ISAK ISAACHSEN.
